HENRY WEIMAR, OF ALLENDALE, NEW JERSEY.

PAINT-CAN ATTACHMENT.

1,176,009.

Specification of Letters Patent. Patented Mar. 21, 1916.

Application filed November 20, 1914. Serial No. 873,128.

To all whom it may concern:

Be it known that I, HENRY WEIMAR, a citizen of the United States, and a resident of Allendale, in the county of Bergen and State of New Jersey, have made and invented certain new and useful Improvements in Paint-Can Attachments, of which the following is a specification.

This invention relates to an attachment for paint cans and more particularly to one adapted to receive and retain paint brushes and hold the same in an accessible position.

An object of the present invention is to provide an attachment preferably made of wire and bent to form a plurality of outstanding loops collectively defining a rack for the reception of paint brushes, holding them within the can, allowing the paint to drip therein.

A further object is to provide a rack in which the various outstanding loops are disposed below the upper edge of the can and rest against the inner surface of can side walls, thus allowing the brushes to be forcibly thrust between the loops without the danger of injuring, bending or distorting the same on account of the thrust being taken up by the side walls of the can.

A further object is to provide a rack with upwardly extending attaching arms adapted to engage the side walls of the can, projecting over the upper edges thereof to thus rigidly support the main or body portion of the rack a considerable distance below the upper edge of the can, eliminating to a large degree the chances of the rack being accidentally knocked or brushed from the can during use.

A further object is to provide a rack of the class mentioned in which the outstanding loops are successively or gradually enlarged, providing for or accommodating brushes of different sizes, the general plan or contour of the rack being such however, that it conforms to the curvature of the side walls of the can against which it is adapted to rest.

With the foregoing and other objects in view which will appear as the description proceeds, the invention resides in the combination and arrangement of parts and in the details of construction hereinafter described and claimed, it being understood that changes in the precise embodiment of the invention can be made within the scope of what is claimed without departing from the spirit of the invention.

In the drawings accompanying this specification and forming a part thereof, the preferred embodiment of my invention is illustrated in which:—

Figure 1 is a view in perspective of a paint can with a portion of the side walls removed disclosing my improved paint brush holder rack attached to the side walls and supporting paint brushes. Fig. 2 is a plan view of the foregoing with the paint brushes omitted. Fig. 3 is a view in perspective of the paint can attachment or rack.

Referring to the drawings in which similar reference numerals designate corresponding parts throughout the several views, 5 represents a paint can in connection with which my improved or novel brush holder is to be used, though it is to be noted in this connection that it may be used with buckets, 75 pails or analogous articles and may support brushes of all types or other similar articles.

The brush holder, proper, includes the central or body portion 6 from which projects the outstanding loops 7. The body 80 portion and outstanding loops define a rack preferably formed of a single length of wire, sufficiently rigid to withstand hard and continued usage and at the same time embodying a degree of elasticity consistent with the 85 engagement and resilient securing of the brushes as illustrated in Fig. 1.

The end of the portions of the rack are turned upwardly and looped upon themselves to form the upstanding resilient clips, 90 there being one of these clips at each end of the rack. The outlying arms at the ends of these clips extend for a considerable distance below the rack proper so as to resiliently engage and obtain a secure purchase 95 upon the side walls of the can.

From the foregoing it will be noted that the rack is positioned below the upper extremity of the clips and is accordingly supported below the upper edge of the can and thus protected against accidental displacement, allowing the attachment to be used upon cans or paint buckets which are being constantly carried up and down ladders or moved from place to place.

The central or body portion of the rack from which the outstanding loops project is arcuate in contour allowing the rack to fit within a paint can and providing that the rear extremity at each loop will bear against and be reinforced by the side walls of the can, the resiliency of the entire device being

such that it may be used with cans of various sizes and forms. The outstanding loops define ledges or shoulders between which the brushes are interposed or upon which they 5 may rest, the former position holding the brushes in an upright and therefore accessible manner and allowing the paint to drip into the cans from each brush.

In the practical use of this rack, I have 10 found it exceedingly convenient, in that heretofore it has been necessary to rest or support the brush upon the edge of the can, causing the latter in time to become covered or coated with paint and in turn to cause the 15 handle of the brush to be smeared therewith. Furthermore, in ascending or descending a ladder, it is usually necessary, for the safety of the painter, to grasp the same with one hand, and in many other instances to utilize 20 one hand in holding on to a support to prevent falling. As the paint can in such instances is carried in the other hand, it is difficult to balance the brush on the edge of the paint can, or to carry it in the hand 25 which carries the can. This difficulty is entirely obviated by the use of the rack hereinbefore described, the same offering a secure support for the brush with little or no chance of its falling, and leaving the hand 30 or hands free, one to carry the can, and the other to hold to a support in moving from place to place. Furthermore, the rack may be used for wiping or removing the excessive paint from the brush in the operation of 35 painting, instead of utilizing the edge of the can for such purpose, as has heretofore been the custom, thus avoiding all danger of the rim becoming covered or smeared with paint as well as the outer sides of the can. Furthermore, I have found the rack useful in 40

supporting a brush or brushes when the latter are not in service, the can being filled to such an extent with water, turpentine, or other liquid, into which the lower ends of the brushes might be submerged, and thereby prevented from becoming hard or stiff, and also from being bent or curled as is the case when the brushes are allowed to be supported on the bottom of the can. 45

It is to be noted in connection with my improved device that while the rack proper is located entirely within the can, and below the upper edge thereof, and extends in a direction toward the center of said can, yet it is located wholly to one side thereof, and 50 therefore out of the way when it is desired to dip the brush into the paint contained within the can; in other words, it in no wise interferes in the operation of inserting the brush into the can or in withdrawing the 55 brush therefrom.

Having thus carefully described my invention and what I claim is:—

The combination with a paint can of a rack disposed therein and including a plurality of outstanding loops, the fixed ends of said loops arranged in the arc of a circle and bearing against the interior walls of said paint can below the upper edge thereof, and resilient clips carried by said rack and projecting over and engaging the upper edge of 60 said paint can. 65

Signed at Allendale, in the county of Bergen and State of New Jersey, this 14" day of November, A. D. 1914.

HENRY WEIMAR.
